UNITED STATES PATENT OFFICE.

BENJAMIN H. TEAGUE, OF PHILADELPHIA, PENNSYLVANIA.

DRILL-SUPPORT.

1,052,767.

Specification of Letters Patent. Patented Feb. 11, 1913.

Application filed March 11, 1912. Serial No. 682,869.

To all whom it may concern:

Be it known that I, BENJAMIN H. TEAGUE, a citizen of the United States, residing at Philadelphia, in the county of 5 Philadelphia and State of Pennsylvania, have invented certain new and useful Improvements in Drill-Supports, of which the following is a specification.

My invention relates to improvements in 10 drill supports, and more particularly to an improved support adapted to be secured to a work bench, and permit the employment of an ordinary breast drill as a bench drill, the object of the invention being to provide 15 a support of this character which may be readily secured to a work bench, which permits a breast drill to be attached thereto or detached therefrom, and which enables the drill to be moved vertically during its operation.

A further object is to provide a device of 20 this character of extremely simple inexpensive construction, which enables the attachment of any ordinary form of breast drill, 25 and which will most effectually perform the functions for which it is intended.

With these and other objects in view, the invention consists in certain novel features 30 of construction and combinations and arrangements of parts, as will be more fully hereinafter described and pointed out in the claims.

In the accompanying drawings: Figure 1, is a view in side elevation illustrating my 35 improvements. Fig. 2, is a fragmentary view in longitudinal section through the upper portion of the support and the drill. Fig. 3, is a view in section on an enlarged scale on the line 3—3 of Fig. 2. Fig. 4, is a 40 view in elevation at right angles to Fig. 1. Fig. 5, is a view in section on an enlarged scale on the line 5—5 of Fig. 4. Fig. 6, is a view in section on an enlarged scale on the line 6—6 of Fig. 1. Fig. 7, is a view in section on the line 7—7 of Fig. 1. Fig. 8, is a 45 view in section on the line 8—8 of Fig. 1.

1, represents a work bench and 2 a bracket secured thereto. The bracket 2 has a lower fixed jaw 3, and an upper movable jaw 4, 50 the latter having a dove-tailed groove 5 in one end to slide upon a dove-tailed guide 6 on bracket 2. This jaw 4 is operated by a screw 7 which projects through the lower jaw 3, and is screwed into the upper jaw 4. 55 The opposed faces of the jaws 3 and 4 are provided with transversely elongated teeth

8 which are forced into the upper and lower surfaces of the bench 1, and prevent any pivotal movement of the bracket 2.

The bracket 2 is made with an outwardly 60 projecting work supporting foot 9 at its lower end, and at its upper end is provided with integral parallel uprights 10 which are spaced apart the desired distance and at their upper ends are made with lugs 11 projecting at right angles to the uprights, and connected at their outer ends by a cross bar 12. These lugs 11 and the cross bar 12 are made with grooves 13 on their inner faces to receive a block 14, and this block 14 has an 65 opening 15 constituting a bearing for the restricted upper end 16 of an operating screw 17. The two diameters of the screw 17 provide a shoulder 18 against the lower face of block 14 to prevent any upward 70 movement of the screw, and a washer 19 is secured on the upper end of the screw by means of a pin 20 and located against the upper face of block 14 to prevent any downward movement of the screw. A hand wheel 75 21 is secured on the upper end 16 to facilitate the turning of the screw, but the mounting of the screw in the block 14 prevents any longitudinal movement of the screw. The threaded portion of screw 17 projects 80 through and engages internal screw-threads in an opening through a lug 22, which is fixed to a slide 23. This slide 23 moves 85 against the outer face of the uprights 10, and is provided with guides 24 projecting at 90 an angle from the slide 23 and sliding on the uprights 10 to hold the slide against the uprights, yet permit the slide a free vertical movement when adjusted by the screw.

25, represents one ordinary type of breast drill with the breast engaging end removed. This drill is secured to the slide 23 by means of a screw 26, which extends through an opening 27 in the slide, and is screwed into a threaded socket piece 28 on the lower portion of the drill, while the upper end of the drill is held in place by means of a bracket 29 which is of the general angular form shown, and is secured to the upper portion of the slide by bolts 30 and nuts 31. These bolts 30 project through slots 32, so that the bracket 29 may be adjusted vertically according to the size of the drill, and the horizontal member of said bracket is made with an opening 33 of two diameters 100 to receive the restricted upper end of the drill, and also accommodate a screw 34 105 110

which is projected through the opening and screwed into the socket 35 in the upper end of the drill. As I preferably employ an angular head on the screw 26, the bracket 2 is 5 recessed as shown at 36 to allow the head of this screw to pass through the bracket if it is necessary to move the drill such a distance.

The slide 23 is provided with a slot 37 10 which enables the attachment of a different form of drill and while I have set forth a particular construction adapted for a particular style of breast drill, I would have it understood that the device may be modified 15 for the accommodation of other forms of drill.

In operation, the work 38 is supported 10 upon the foot 9, and hand wheel 21 turned to move the drill down so as to engage the 20 work. As the drill is revolved, it is fed downwardly by turning this hand wheel 21, and the work drilled.

When the drill is desired for use as a 25 breast drill, it is simply necessary to detach it from my improved support, and put it to its natural uses.

Various slight changes might be made in the general form and arrangement of parts described without departing from my invention, and hence I do not limit myself to the 30 precise details set forth, but consider myself at liberty to make such changes and alterations as fairly fall within the spirit and scope of the appended claims.

Having thus described my invention, what I claim as new and desire to secure by Letters Patent is:

1. A device of the character described,

comprising a bracket, means for clamping the bracket to a work bench, parallel uprights on the bracket, lugs projecting at right angles to the uprights, a bar connecting the outer ends of said lugs, said lugs and said bar having grooves therein, a block positioned in said grooves and having an opening therethrough, a screw having a restricted upper end projected through the opening in the block, means for holding the screw against vertical movement in the block, means on the upper end of the screw 40 for turning the same, a drill supporting slide mounted on said uprights, and a lug fixed to said slide and having a screw-threaded opening receiving the screw, substantially as described. 45

2. A device of the character described, comprising a bracket, uprights on the bracket, a drill supporting slide mounted to move vertically on the uprights, a screw supported in the uprights and constructed 60 to move the slide vertically, a screw projected through the slide and adapted to engage a drill, said slide having longitudinal slots in its upper portion, an angle bracket having an opening therein to receive the 65 upper end of a drill, bolts projected through said slots and through the bracket, and nuts 70 on the ends of said bolts, substantially as described.

In testimony whereof I have signed my 70 name to this specification in the presence of two subscribing witnesses.

BENJAMIN H. TEAGUE.
